UNITED STATES PATENT OFFICE

2,037,225

WINDOW CONSTRUCTION

Louis Fradella, Brooklyn, N. Y.

Application May 27, 1935, Serial No. 23,593

1 Claim. (Cl. 20—50)

One object of this invention is the provision of a rain- and wind-proof weather strip for combination hinged and slide windows, the weather strip being so constructed and applied to the window as to securely seal the same when in closed position.

The above and other objects will become apparent in the description below, in which characters of reference refer to like-named parts in the accompanying drawing.

Referring briefly to the drawing, Figure 1 is a front elevational view, partly in section, of a combination hinged and slide window in closed position.

Figure 2 is a cross-sectional view taken on the line 2—2 of Figure 1.

Figure 3 is a view similar to Figure 2, with the windows swung into open position.

Figure 4 is a perspective view, partly in section, of one of the slide rails of the window.

Figure 5 is a perspective view, partly in section, of another of the slide rails of the window.

Referring in detail to the drawing, the numeral 10 represents one side of the window frame and 25 11 the other, the sash weights 12 being carried therein. The inner walls of the frame are provided with the usual vertical grooves 13 and 14—15. In these grooves hollow rails 16 and 17 are slidably mounted, being retained in the 30 grooves by means of guards 18 projecting from the groove bases through slots 19 in the rails and widened heads 20 on the guards.

One pair of rails 16 provides the mounting for the window 22, and the other pair 16—17 provides the mounting for the window 23. One rail 16 is provided with a pair of spaced-apart arms 21 in the ends of which the window 22 is pivotally mounted near one end. The rail 17 is similarly provided with a pair of spaced apart 40 arms 24, shorter than the arms 21, in the ends of which the window 23 is pivotally mounted.

Each of the three rails indicated by the numeral 16 is provided with a projecting hook 25 extending parallel with the wall of the rail. The 45 sash 22 is provided on each side with a slot 26 in which the hook 25 registers when the windows are swung into closed position, thus sealing the window against the rail. One side of the sash

23 is similarly provided with a slot 26, for the same purpose, while the other side of this sash has a slot 27 therein at right angles to the slot 26. The rail 17 is provided with a tongue 28 which registers in the slot 27 when the sash 23 is swung into closed position.

A hand latch 29 is provided at the top of the right-hand side of each sash to release the sash so that it may be swung out of closed position. The rails 16 opposite those having the arms 21 and 24, are provided with supports 30 on which the bottom ends of the sashes rest when the latter are in closed position, to prevent sagging of the sashes about their pivots.

It is obvious from the above that when the windows are in swung-in position, and used as simple slide windows, they are secure against rain or wind leaks.

Obviously, modifications in form and structure may be made without departing from the spirit of the invention.

I claim:

In a combination hinged and slide window, a window frame having vertical grooves therein, hollow rails slidably mounted in said grooves, 25 said rails having vertical slots therein, guards extending from the bases of said grooves through said slots and having enlarged heads lying in said rails to retain said rails in said grooves, arms extending from one of said rails at one 30 side of said frame and having a window sash pivotally mounted thereon, said sash including a pair of opposite vertical side members having the glass window pane mounted therebetween, each of said side members being substantially 35 rectangular in cross section and having an edge adapted to lie against the rail when the window is closed and a front and a back face on either side of said edge, a slot in the front face of one of said side members and a slot in the back 40 face of the other of said side members, a right-angled extension on each of said rails having a hook thereon extending parallel with the surface of the rail, said hooks registering in said slots when the window is closed, to seal said window 45 when the window is swung into closed position.

LOUIS FRADELLA.
